[57] **CLAIM**

The ornamental design for a combined pesticide and herbicide hopper with a dust agitator, as shown and described.

DESCRIPTION

FIG. 1 is a reduced perspective view of a combined pesticide and herbicide hopper with a dust agitator with the lid in open position showing our new design;
FIG. 2 is a top plan view with the lid in closed position;
FIG. 3 is a front elevational view of FIG. 2;
FIG. 4 is a right side elevational view, the left side being a mirror image thereof;
FIG. 5 is a rear elevational view of FIG. 2;
FIG. 6 is a bottom plan view of FIG. 2;
FIG. 7 is a top plan view with lid in open position.

FIG. 1.

FIG. 2.

FIG. 3.

FIG. 4.

FIG. 5.

FIG. 6.

FIG. 7.
